FUEL INJECTION PUMP

Herbert C. Edwards, Canal Fulton, Ohio, assignor
to The Timken Roller Bearing Co., Canton,
Ohio, a corporation of Ohio

Application August 22, 1946, Serial No. 692,299

18 Claims. (Cl. 103—2)

1 This invention relates to pumps, particularly single plunger fuel injection pumps for multi-cylinder compression ignition engines. The invention has for its principal objects to provide a simple, economical and compact pump of the above type that will deliver a correct quantity of fuel to each working cylinder of the engine in proper timed relation to the working cycle thereof; that is adjustable to vary the timing and quantity of the fuel injection; that will provide for automatically controlling the quantity of the fuel injection in accordance with the speed of the engine; that will provide for setting the fuel quantity control means for different engine speeds; that will provide a unit injection and supply pump assembly in which the supply pump is operated by the injection pump; and that will obtain other advantages hereinafter appearing. The invention consists in the governor controlled unit injection and supply pump and in the parts and combinations and arrangements of parts hereinafter described and claimed.

In the accompanying drawings, which form part of this specification and wherein like symbols refer to like parts wherever they occur,

Fig. 1 is a top plan view of a governor controlled fuel pump embodying my invention,

Fig. 2 is a side elevational view of the control lever side of said pump,

Fig. 3 is an end elevational view of the supply pump end of said pump,

Fig. 4 is an enlarged central vertical longitudinal sectional view on the line 4—4 in Fig. 5,

Fig. 5 is an enlarged vertical cross-sectional view through the supply pump end of the pump, the section being taken on the line 5—5 in Fig. 2,

Figs. 6, 7, 8, 9 and 10 are vertical cross-sectional views on the lines 6—6, 7—7, 8—8, 9—9 and 10—10, respectively, in Fig. 4,

Fig. 11 is a fragmentary vertical longitudinal sectional view on the line 11—11 in Fig. 7; and

Fig. 12 is a vertical cross-sectional view on the line 12—12 in Fig. 4.

The single plunger, governor controlled, multiple injection fuel pump shown in the accompanying drawings is adapted for use with a six-cylinder, four-cycle, compression ignition engine (not shown). Said fuel injection pump comprises an elongated oil containing housing 1 having axially aligned cylindrical end openings 2 and 3, respectively, and a top opening 4 closed by a removable cover plate 5 having a hooded breather opening 5a therein. A drive shaft 6 extends into the housing 1 through the end opening 2 thereof and is adapted to be driven by or in unison with

2 the engine at one-half engine speed. The drive shaft 6 is supported in two rotary antifriction bearings, preferably taper roller bearings 7 and 8, mounted respectively in a cover or cap 9 for the outer end of the end opening 2 of the housing 1 and in a cross wall 10 formed in said housing intermediate between the ends thereof. The end cap 9 is removably secured to the housing 1 by means of socket head cap screws 11 and has a cylindrical plug portion 9a that fits within the end opening 2 of said housing. A suitable oil seal 12 surrounds the drive shaft 6 between the outer end of the end cap 9 and the inner raceway member of the roller bearing 7.

Mounted in the end opening 2 of the housing 1 in endwise abutting relation to the inner end of the plug portion 9a of the cap 9 for said opening is an annular holder 13 which surrounds the shaft 6 and supports three circumferentially spaced conical cam rollers 14 that are disposed radially of said holder and taper inwardly towards the axis thereof. The conical cam rollers 14 are located in pockets 15 provided therefor in the annular holder 13 and are journaled on pins 16 mounted in radial bores provided therefor in said holder. A dowel pin 17 extends through the end cap 9 lengthwise thereof and terminates at its inner end in a crank portion 17a which fits within a radial slot 18 provided therefor in the adjacent end of the annular roller holder 13. By turning the dowel 17, the roller holder 13 may be rotated in the supporting opening 2 therefor in the housing 1, after which said dowel and said roller holder may be locked in the desired position of rotary adjustment by means of a nut 17b threaded on the exposed outer end of said dowel.

The drive shaft 6 has an enlarged tubular inner end portion 6a on which is mounted an annular cam member 19 having a conical cam face 20 at its holder opposing end with six circumferentially spaced peaks 20a adapted to successively engage three cam rollers 14 journaled in the holder 13. The annular cam member 19 is splined to the shaft 6 for rotation therewith and for axial sliding movement relative thereto by the cam rollers 14, the cam member being forced inwardly along the large tubular end portion 6a of said shaft when a rise or peak 20a on the cam face 20 of said cam member engages a cam roller 14. The splined connection between the cam member 19 and the enlarged tubular inner end portion 6a of the shaft 6 preferably comprises longitudinal ribs 21 that are formed in said cam member and fit in longitudinal slots 22 in said enlarged tubular end portion of said shaft. The rotary and axially slid-

able cam member 19 is yieldably held in engagement with the cam rollers 14 by means of a coil compression spring 23 that is mounted around the enlarged tubular inner end portion 6a of the drive shaft 6 with one end seating against said cam member and with the other end seating against the opposing end face of a hexagonal edge cam 24 fixed to said tubular portion between a collar 25 thereon and the adjacent end of the inner raceway member of the roller bearing 8.

Extending into the tubular inner end portion 6a of the drive shaft 6 through the open inner end thereof is a pump plunger 26 which rotates with said tubular end portion but is reciprocated axially therein by the annular cam member 19 splined theron. The reciprocating motion of the cam member 19 is imparted to the pump plunger 26 through a transfer plate 27 which is mounted in the reduced blind end of the tubular portion of the drive shaft 6 and has an undercut slot 27a, which opens through one side of said plate and is adapted to rotatably receive the adjacent headed end 28 of said plunger, and exterior lugs 29 that fit in cross notches 30 in the internal ribs or splines 21 in the drive shaft receiving bore of said cam member and are slidable with said splines in the longitudinal slots 22 in said tubular portion of said drive shaft.

The rotary driving connection between the drive shaft 6 and the cam reciprocated pump plunger 26 comprises a sleeve 31 supported in the enlarged tubular end portion 6a of said shaft 6, diametrically opposed pins 32 fixed to said tubular end portion of said plunger and extending radially inwardly thereof into left-hand helical slots 33 formed in said sleeve, and a ring or spider 34 that is secured to said pump plunger by means of a diametral pin 35 rigid therewith and has peripheral lugs 36 that are located on a diameter at right angles to said pin and fit in straight longitudinal slots 37 provided therefor in said sleeve between the helical slots 33 therein. By this arrangement, the plunger 26 is adapted to rotate with the shaft 6 while being reciprocated axially thereof by the cam member 19 and the pin-and-helical slot connections between said shaft and the sleeve 31 produces relative rotation of said plunger and shaft when said sleeve is slid axially of said shaft in either direction. The pin 35 fixed to the plunger 26 is axially slidable in the openings provided therefor in the ring 34 so as to accommodate misalignment of said plunger and still drive said plunger at the same velocity of rotation as the shaft 6.

The rotary and reciprocable pump plunger 26 works in a pump cylinder or barrel 38 having an enlarged intermediate portion 39 that fits within the end opening 3 of the pump housing 1 and a larger head portion 40 that abuts endwise against the outer face of said housing around said end opening. The outer end of the axial pump plunger receiving bore of the pump cylinder or barrel 38 is closed by means of a threaded plug 41, and the working end of the plunger 26 cooperates with said bore to form a pressure chamber or space 42 at the closed outer end thereof. The pump barrel 38 has a plurality of fuel delivery or discharge passageways 43 therein, one for each of the six working cylinders of the engine supplied by the pump. The fuel discharge passageways 43 are spaced apart equally about the axis of the pump barrel or cylinder 38 with their inner ends opening into the plunger supporting bore inwardly of the pressure chamber 42 and with their outer ends opening through the outer

end face of the head 40 of said cylinder where they are threaded for connection with fuel injection lines or conduits 44 that lead to the fuel injection nozzles (not shown) for the respective working cylinders of the engine. The pump cylinder 38 also has a single combination fuel inlet and fuel by-pass passageway 45 therein whose inner end opens into the plunger supporting bore inwardly of the inlet ends of the fuel discharge passageways 43 and whose outer end opens outwardly through the peripheral surface of the enlarged head end 40 of said pump cylinders.

The pump plunger 26 has an annular groove 46 therein adjacent to the working end thereof and adapted, in the retracted position of said plunger, to communicate with the single combination inlet and by-pass passageway 45. The plunger 26 also has six equally spaced longitudinal fuel inlet and pressure relief grooves 47 in the periphery thereof that lead rearwardly from the rear edge of the annular peripheral groove 46 far enough to establish communication between the fuel inlet and by-pass passageway 45 and said annular groove during the entire length of either the suction or pressure stroke of the plunger when any one of the six longitudinal grooves is in communication with said fuel inlet and by-pass passageway. The injection pump plunger also has a single longitudinal peripheral indexing distributing groove 48 that extends from the annular groove through the working end of the plunger 26 and is adapted to provide continuous communication between said annular groove and the pressure chamber 42 at the working end of said plunger. When the plunger 26 is rotated, the single peripheral distributing groove 48 therein is adapted to successively register with the six discharge passageways 43 in the pump cylinder 38 during the reciprocating movement of said plunger, and the six longitudinal metering and pressure relief grooves 47 are adapted to successively register with the fuel inlet and by-pass passageway 45.

The barrel or cylinder 38 of the fuel injection pump is held in the end opening 3 of the pump housing 1 by means of an end cap or plate 49 which is secured by socket head cap screws 50 to the adjacent end of said housing and has a cylindrical hole therethrough adapted to snugly receive the cylindrical head portion 40 of said pump barrel or cylinder. The hole in the retainer plate or cap 49 has an annular lip or flange 51 at the outer end thereof that overlaps the head 40 of the barrel member 38 and retains the same in said hole. The barrel member 38 is prevented from rotating in the plate 49 by means of a dowel pin 49a which is fixed to said plate and fits within a recess provided therefor in the head 40 of said barrel member. The head supporting opening 60 in the retainer plate is sealed against leakage by two sealing rings 52 located therein, one on each side of the outer end of the fuel inlet and by-pass passageway 45 in the barrel head 40.

The pump chamber 42 is supplied with fuel by a supply pump mechanism operated from the drive shaft 6 of the fuel injection pump. This supply pump comprises a double acting piston 53 mounted in a bore 53a that extends through the retainer plate 49 from side to side thereof crosswise of the barrel head 40 supported therein. The piston 53 is reciprocated by means of a rocker shaft 54 that is located in the housing 1 above and parallel with the drive shaft 6 and plunger 26 and extends through the pump barrel supporting end wall of said housing and is journaled in a

suitable bushing 55 provided therefor in said end wall. The outer end of the bushing receiving opening is counterbored to receive a suitable annular oil seal 56, which bears axially against the outstanding flange of a collar 55a mounted on the rocker shaft 54 between a crank 57 thereon and the bushing 55. The crank 57 operates in a recess 58 in the inner face of the plate 49 and has a pin 59 that fits within a cylindrical opening provided therefor in a square bushing 60 mounted in a square opening that extends through the piston 53 transversely thereof, whereby said piston is adapted to be reciprocated when said rocker shaft is oscillated. The inner end of the rocker shaft 54 is journaled in a bushing 61 provided therefor in the cross wall 40 of the housing 1; and said shaft is provided adjacent to said wall with a rocker arm 62 having a cam roller 63 journaled on the free end thereof. The cam roller 63 cooperates with the hexagonal edge cam 24 which is fixed to and rotates with the drive shaft 6, whereby said rocker shaft is oscillated by the rotary movement of said drive shaft.

Fuel from a tank or other source of supply (not shown) is supplied to one end of the supply pump piston supporting bore through an inlet fitting 64 threaded therein. The inlet fitting opposing end of the supply pump piston 53 has a spring closed, inwardly opening disk valve 65 therein. Inwardly of this inlet valve 65, the supply pump piston 53 has a radial port 66 therein which opens upwardly into a vertical priming pump chamber or cylinder 67 through a port 66a in the bottom or lower end thereof. Reciprocable in the priming pump chamber 67 is a normally inoperative piston 68 having an opening extending longitudinally therethrough that is normally closed by an upwardly opening, spring seated, disk valve 69. The priming pump piston 68 has an actuating rod 70 extending upwardly therefrom through a bushing 71 that is threaded into the upper end of the priming pump cylinder or chamber 67. An operating knob 72 is removably secured to the exposed upper end of the piston rod 70 by means of a screw 73 and is threaded on the upper end of the piston rod bushing 71 so as to lock the priming pump piston 68 in the lower end of the cylinder 67.

The priming pump cylinder 67 communicates at its upper end with an outlet fitting 74 that is threaded into the end plate 49 above the inlet fitting 64. The outlet fitting 74 communicates through a suitable conduit 75, which may include a filter (not shown) with an inlet fitting 76 that is threaded into the cross bore 53a at the end thereof opposite the inlet fitting 64. This end of the bore 53a has a spring seated inwardly opening inlet valve 77 mounted therein inwardly of the inlet fitting 64. The bore 53a is interrupted between the inlet valve 77 and the piston 53 to form within the end plate 49 a chamber or cavity 78 which extends around the head 40 of the fuel injection pump cylinder or barrel 38 and is in continuous communication with the end of the inlet and by-pass passageway 45 which opens through the peripheral surface of said head of said cylinder or barrel. Interposed between the inlet valve 77 and the opposing end of the piston 53 is a coil compression spring 79 which has one end seated in a recess in said end of said piston and the other end supported in a spring seat member 80 mounted in the bore 53a inwardly of said inlet valve. The piston 53 is reciprocated in one direction against the pressure of the spring 79 by means of the cam actuated rocker shaft 54 and

in the other direction by means of said spring, which also serves to hold the roller 63 on the inner end of the rocker arm 62 of said shaft in engagement with the cam surface of the hexagonal cam 24 which rotates with the drive shaft 6. By this arrangement, the piston 53 operates in one direction of its reciprocating movement to draw fuel through the inlet valve 65 in said piston, thence through the inlet valve 69 in the locked priming pump piston 68 into the cylinder 67 therefor, thence from the priming pump cylinder through the conduit 75 to the inlet fitting 76, thence through the valve 77 into the chamber or cavity 78 in the end plate 49. In the other direction of its reciprocating movement, the piston 53 operates to force the fuel in the chamber or cavity 78 into the inlet and by-pass passageway 45 which opens into the cylinder 38 in which the injection pump plunger 26 operates.

The barrel end plate 49 also has a horizontal bore 81 therein above the level of the supply pump piston 53 and at one side of the priming pump chamber 67. The outer end of the bore 81 is closed by means of a threaded plug 82; and said bore 81 communicates through a port 83 near its closed outer end with the fuel chamber 78 and through a port 84 at its inner end with the priming pump chamber 67 above the level of the normally inoperative piston 68 therein. Reciprocable in the bore 81 is a loosely fitting piston 85 for equalizing the pressure developed by the fuel supply piston 53. This pressure equalizing piston 85 is urged by means of a coil compression spring 86 against a stop stud 82a that projects axially from the inner end of the plug 82 for the outer end of said bore. The axial stud 82a of the closure plug 82 for the bore 81 holds the spring pressed piston 85 therein clear of the port 83 which establishes communication between said bore and the recess or chamber 78 that communicates with the inlet and by-pass passageway 45. Thus, the discharge from the outer end of the supply piston 53 has access to the spring supported end of the pressure equalizing piston 85 through the port 84, while the pressure developed by the inner end of said supply pump piston is transmitted to the other end of said pressure equalizing piston through the port 83. By this arrangement, if the pressure developed at one end of the supply pump piston 53 greatly exceeds the pressure at the other end thereof, the small piston 85 is deflected toward the least pressure. Usually the higher pressure is on the inner end of the fuel supply piston 53, so that the spring 86 is compressed a certain amount. Thus, during operation, the small pressure equalizing piston 85 floats in the bore 81 clear of the stop stud 82a in the outer end thereof.

Located in a horizontal bore 87 in the barrel end plate 49, just above the pressure equalizing piston 85, is a small fuel by-pass or pressure relief piston 88. The outer end of the bore 87 is provided at its outer end with an outlet fitting 89, while the inner end of said bore opens into the priming pump chamber 67 above the normally inoperative piston 68 in the lower end thereof. The by-pass piston 88 is normally pressed inwardly in its supporting bore 87 against a diametral stop pin 91 therein by means of a coil compression spring 92 that has one end seated in the outer end of said piston and the other end seated in the inner end of the outlet fitting 89. The bore 87 has an annular groove 93 therein which extends around the piston 88 and opens into a longitudinal groove 94 that extends to the outlet fitting 89 in the outer end of said bore. The piston 88 operates as a pressure regu-

lating device and is normally held against the stop pin 91 by the pressure of the spring 92 and in covering relation to the annular escape groove 93. However, as the pressure generated on the outer end of the supply pump piston 53 increases, the piston 88 is forced outwardly in the bore 87 against the pressure of the spring 92 until said piston uncovers the annular groove 93 in said bore and allows the fuel to by-pass or escape through the longitudinal groove 94 to the outlet fitting 89 where the surplus fuel is returned to the source of fuel supply through a conduit 95.

When it is desired to prime the fuel injection pump, the operating knob or handle 72 of the priming pump is unscrewed from the bushing 71 and used to manually reciprocate the priming piston 68. This action draws fuel in through the inlet fitting 64 through the valve 65 in the supply pump piston 53, through the valve 69 in the priming pump piston 68 and through the conduit 75 and the valve 77 into the chamber or cavity 78 which communicates with the inlet and by-pass passageway 45 of the fuel injection pump. When the knob 72 is screwed down tightly in its lowermost position, the valve 69 in the priming piston 68 acts after the manner of the valve 65 in the supply pump piston 53, thereby providing a double valve in the discharge side of the supply pump and thus forming a double seal which prevents back flow of pressure from the discharge side of the supply pump.

The operation of the hereinbefore described unit injection and supply pump assembly is as follows: The drive shaft 6 is continuously rotated from the engine at one-half engine speed and the fuel injection plunger 26 rotates with said drive shaft while being reciprocated in the pump barrel or cylinder 38 by a roller actuated cam member 19 splined on said shaft, the pump plunger making one complete rotation for each engine cycle. The six peaks 20a of the cam 20 of the cam member 19 cooperate with the three cam rollers 14 so that the plunger 26 makes six reciprocating cycles for each rotation thereof. The multiple cam face 20 and rollers 14 serve to distribute the injection load around the axis of the plunger 26 and provide a maximum length of roller pin and roller and cam contact. At the same time, the rocker shaft 54 is operated by the hexagonal edge cam 24 on the shaft 6 to impart one complete reciprocating cycle to the supply pump piston 53 for each reciprocating cycle of the injection plunger 26. This reciprocating movement of the supply pump piston 53 causes fuel from the supply tank to be drawn through the inlet valves 65, 69 into the priming pump chamber 67, thence through pipe 75, which contains a fine filter (not shown) and thence through the inlet valve 77 into the fuel chamber 78 where the fuel is forced by said piston into the inlet and by-pass passageway 45 which communicates with the pressure space or chamber 42 of the fuel injection pump through the grooves 46, 47 and 48 in the plunger 26.

During each pressure stroke of the plunger 26, fuel is forced through a discharge passage 43 when the rear edge of the annular groove 46 in said plunger closes the inlet and by-pass passageway 45 and the distributing groove 48 of said plunger registers with said discharge passageway. Fuel injection through this discharge passageway 43 ceases while the pump plunger 26 is still operating on its pressure stroke, and while the distributing groove 48 is still in communication with the discharge passageway 43, when one of the six pressure relief grooves 47 registers with the inlet

5 and by-pass passageway 45. At this point in the pressure stroke of the rotating plunger 26, there is a back flow of the fuel from the discharge passageway 43 to the chamber 78 through the pressure chamber 42, distributing groove 48, annular groove 46, pressure relief groove 47 and inlet and by-pass or overflow passageway 45, thereby reducing the pressure in the discharge passageway 43 to the supply pump pressure and thus preventing nozzle dribble.

As stated above, the piston 88 serves to equalize the pressure at opposite ends of the double acting supply pump piston 53, while the piston 88 serves to by-pass the surplus fuel through the fuel return pipe 95. Any air which collects in the fuel chamber 78 rises to the top of said chamber and slowly escapes through the port 83 into the bore 81 having the loosely fitting pressure equalizing piston 85 therein and thence around said piston and the pressure relief piston 88 to the fuel return conduit 95. On the return or suction stroke of the plunger 26, the positive stroke of the supply pump piston 53 is taking place, which stroke forces the fuel from the chamber 78 into the inlet and by-pass passageway 45 to fill the chamber or space 42 formed by the suction stroke of said plunger. The pump may be adjusted to vary the timing of the fuel injection by turning the dowel pin 17 so as to rotate the cam roller holder 13 relative to the cam member 19.

The quantity of fuel discharged through the discharge passageways 43 may be varied by shifting the sleeve 31 axially in the tubular inner end portion 6a of the drive shaft and thus bring about an angular adjustment of said sleeve and the plunger 26 relative to the drive shaft and a similar angular adjustment of the pressure relief groove 47 in said plunger relative to the inlet and by-pass passageway 45. Thus, if one of the pressure relief grooves 41 of the plunger 26 is in register with the inlet and by-pass passageway 45 during the entire working stroke of said plunger, the fuel is discharged through said passageway and not through the discharge passageway 43. When, however, the sleeve 31 is shifted axially the time of the opening of the passageway 45 is delayed, thus causing a delivery of fuel through the fuel discharge passageway 43. The fuel quantity control sleeve 31 is adjusted axially of the drive shaft 6 therefor by means of a centrifugal governor mechanism that is responsive to the speed of said shaft. This governor mechanism preferably comprises a spider 96, which is mounted on the end of the tubular inner end portion 6a of the drive shaft 6 and has a resilient rotary driving connection therewith. This connection comprises two helical coil springs 97 mounted in an external annular groove 97a in the drive shaft 6, a key 99 fixed to said drive shaft and interposed between two adjacent ends of the springs 97 and a screw 100 threaded through the hub of the governor spider 96 and extending into said groove between the other two adjacent ends of said springs. This arrangement provides a resilient drive which absorbs or cushions shocks due to variation in angular motion of the rotating parts caused by the different injection impulses which take place during rotation.

Supported on pivot pins 101 mounted in the spider transversely of the rotary axis thereof is a series of centrifugal weights 102 that are grouped around a thrust spool 103 that is sleeved on the barrel member 38 for sliding movement axially thereof and are adapted to swing outwardly away from said spool under the action of

centrifugal force from the axis about which the spider rotates. The thrust spool 103 serves to limit the inward swinging movement of the weights while the outward swinging movement thereof is limited by stops 104 formed on the spider. The thrust spool 103 is located opposite the inner end of the drive shaft 6 in endwise abutting relation to a thrust collar or ring 105 that is mounted for rotary but non-axially sliding movement on the exposed end of the fuel quantity control sleeve 31. The connection between the thrust ring 105 and the sleeve 31 comprises a split ring 106 that fits in annular grooves provided therefor in said ring and sleeve. The pivot ends of the centrifugal weights 102 have fingers 107 that extend inwardly therefrom on one longitudinal side edge thereof and have curved surfaces 108 adapted, when said weights swing outwardly, to bear against the rotary thrust collar on the control sleeve 31 and thus shift the latter axially in the tubular end portion 6a of the drive shaft 6, whereby the pin-and-helical slot connections 32, 33 between said sleeve and the drive shaft 6 serve to change the angular relationship of said shaft and sleeve and thus vary the quantity of fuel delivered by the plunger 26 through the fuel delivery passageways 43.

The outward swinging movement of the centrifugal governor weights 102 shifts the fuel control sleeve 31 axially of the drive shaft 6 in a direction that will decrease the quantity of fuel delivery. When the governor weights 102 swing inwardly due to a decrease in speed of the drive shaft 6, the sleeve 31 is shifted axially in the tubular end portion 6a of the drive shaft 6 in the direction of increased fuel delivery by means of a governor control system enclosed within the housing 1 and adjustable from the exterior thereof. This governor control system comprises a thrust yoke 109 which is rotatably supported for vertical swinging movement longitudinally of the thrust spool 103 on a cross-shaft 110 that extends from side wall to side wall of the housing 1 above the level of said spool and is journaled in said side walls with one end bent at right angles to form an operating handle 111 located exteriorly of said housing. The two downwardly extending branches of the thrust yoke 109 straddle the rocker shaft 54 and the pump barrel 38 and terminate at their lower ends in forwardly curved fingers 112 that seat against the thrust spool 103 at the end thereof remote from the end that bears against the thrust collar 105 carried by the sleeve 31. The upper end of the thrust yoke 109 has a stop screw 113 threaded therethrough which abuts against a seat 114 provided therefor in the adjacent end wall of the housing 1 and serves to limit the swinging movement of the fingers 112 of the depending arms of said yoke in the direction of the governor spool 103. This stop screw serves to limit the inward travel of the governor weights 102 and the sleeve 31 and thus constitutes a limiting stop for the maximum usable quantity of fuel.

The governor control system also includes a control shaft 115 that extends from side wall to side wall of the housing 1 above the cam seating spring 23 and has its ends journaled in bearings 116 that project inwardly from said side walls and has one end located exteriorly of said housing and provided with a control lever 117 whose swinging movement is limited in one direction by a stop screw 118 threaded in said housing on one side of said lever and in the other direction by a stop screw 119 threaded into said housing on the other

side of said lever. A control yoke 120 has V-notches 121 in the lower ends of its downwardly extending branches; and these notched ends are supported on knife edges 122a formed on the upper ends of pins 122 that are supported in vertical bores formed in lateral extensions of the control shaft bearings 116. The knife edges 122a are located at one side of the control shaft 115 on the side thereof remote from the thrust yoke 109; and said control yoke 120 has a lug 123 projecting laterally and thence downwardly from the top thereof in overhanging relation to said control shaft 115. The control yoke shaft 115 has a lug 124 extending upwardly therefrom for rotation therewith. A coil tension spring 125 has its upper end hooked into an opening provided therefor in the top of the yoke 120 and has its lower end hooked into an opening provided therefor in the upwardly projecting lug 124 on the control shaft. Extending longitudinally of the housing 1 above the supply pump actuating rocker shaft 54 and between the thrust yoke 109 and the control yoke 120 is an extensible link comprising a rod 126 and end fittings 127 axially slidably thereon and terminating at their remote ends in pointed or tapered portions 128. A coil compression spring 129 is sleeved on the axially extensible link with its ends fixed to the end members 127 thereof and tends to force them apart and hold them one with its pointed end 128 rockably supported in a conical recess 130 in the thrust yoke 109 and the other with its pointed end similarly supported in a similar recess 131 in the control yoke 120. The control lever 117 may be operated to compress the oil compression spring 129 to keep the fingers 112 of the thrust yoke 109 in contact with the governor spool 103 through the tension spring 125, the upper end of which is attached to the control yoke 120 and the lower end of which is attached to the lug 124 on the control shaft 115. As the lug 120 is rotated toward the drive end of the pump, it swings in an arc which, at its extreme, passes through the knife edge center of rotation 122a of the control yoke 120. In this position of the lug 124 the tension spring 125 has no effect on the governor spring system. As the control shaft lug 124 is rotated in the other direction away from the drive end of the pump, the effective lever arm in the line of action of the tension spring 125 increases. At the same time, the length of the tension spring 125 is increased, thereby increasing the load of said spring and transferring such additional load through the compression spring 129 to the thrust yoke 109 and thus increasing the load applied to the governor spool 103 to keep the centrifugal governor weights 102 in closed position. By reason of this additional spring load on the governor spool a higher speed of rotation of the drive shaft 6 is required to enable the centrifugal weight force to overcome the spring force and shift the control sleeve 31 in the direction of decreased fuel delivery. Thus, by adjusting the control lever 117, the spring combination 125 and 129 may be regulated to match the centrifugal weight force so as to provide a higher spring weight at higher speeds as well as a higher spring load. For example, if both lever arms of the thrust yoke are of equal length, the combined effective rate of both springs along the line of action on the control sleeve 31 will vary inversely as the square of the ratio between the tension and compression spring lever lengths. For each speed setting of the control lever 117, there are two position of axial adjust-

ment of the fuel control sleeve 31, one position corresponding to wide open throttle and the other position corresponding to no throttle. As stated above, the compression spring 129 and the tension spring 128 cooperate to produce an over-all spring rate that matches the weight forces, which are combined through the lever arms about the knife edges. The governor control system provides constant governor regulation over a wide range of engine speeds, and the forces required to adjust the system to any given speed are small as applied to the control lever 117 and there are only two springs required.

The governor spool opposing faces of the depending arms of the thrust yoke 109 are formed just below the thrust yoke supporting shaft 110 with flat seats 132; and said yoke supporting shaft has a block 133 fixed thereto that extends across said seats. By this arrangement, the exposed handle end 111 of the yoke supporting shaft 110 may be manipulated to so rotate the said shaft in a direction that will cause the ends of the block 133 thereon to bear against the seats 132 on the thrust yoke 109 and swing the latter in a direction that will overcome the pressure of the governor springs 125, 129 and allow the governor weights 102 to expand to their outmost position and move the sleeve 31 to its outer position in the shaft 6, whereby all of the fuel is by-passed and there is no fuel delivery. Thus, the lever 111 constitutes a shut off lever to stop delivery of fuel regardless of the position of the throttle lever 117.

Obviously, the hereinbefore described unit governor controlled fuel injection pump assembly admits of considerable modification without departing from the invention. Therefore, I do not wish to be limited to the precise arrangement shown and described.

What I claim is:

1. A fuel injection pump for a multi-cylinder internal combustion engine comprising a stationary cylinder having a combination fuel inlet and by-pass passageway opening into said cylinder through a single opening and a plurality of fuel discharge passageways, a plunger working directly in said cylinder, means for simultaneously reciprocating and rotating said plunger in said cylinder, means formed on said plunger for successively placing said discharge passageways in communication with the pressure space of said cylinder in intermittent successive positions of the rotary and reciprocating movement of said plunger, and means formed on said plunger and operable during each pressure stroke thereof for placing said pressure space first in communication with said inlet and by-pass passageway through said single opening thereof, then cutting off communication between said pressure space and said single opening of said inlet and by-pass passageway and then reestablishing communication between said pressure space and said single opening of said inlet and by-pass passageway when any one of said discharge passageways is in communication with said pressure space.

2. The combination set forth in claim 1 wherein the means for rotating said plunger is adjustable to change the phase relationship between said plunger and plunger rotating means and thereby vary the quantity of fuel discharged through said discharge passageways, and said last mentioned means is automatically controlled by means responsive to the speed of rotation of said plunger rotating means.

3. A fuel injection pump for a multi-cylinder internal combustion engine comprising a sta-

tionary cylinder having a single combination fuel inlet and by-pass passageway opening into said cylinder through a single opening and a plurality of fuel discharge passageways, one for each engine cylinder, spaced apart equally about the axis of said cylinder, a plunger working directly in said cylinder, means for rotating said plunger in said cylinder, means for imparting to said plunger during each complete rotation a number of reciprocating cycles corresponding to the number of engine cylinders, means formed on said plunger for successively placing said discharge passageways in communication with the pressure space of said cylinder in intermittently successive positions of the rotary and reciprocating movement of said plunger, and means formed on said plunger and operable during the pressure stroke thereof for placing said pressure space first in communication with said inlet and by-pass passageway through said single opening thereof, then cutting off communication between said pressure space and said single opening of said inlet and by-pass passageway and then reestablishing communication between said pressure space and said single opening of said inlet and by-pass passageway when any one of said discharge passageways is in communication with said pressure space.

4. A fuel injection pump for a multi-cylinder internal combustion engine comprising a cylinder having a single combination fuel inlet and by-pass passageway opening into said cylinder through a single opening and a plurality of fuel discharge passageways, one for each engine cylinder, a plunger working directly in said cylinder, means for simultaneously reciprocating and rotating said plunger in said cylinder, means formed on said plunger for successively placing said discharge passageways in communication with the pressure space of said cylinder in intermittently successive positions of the rotary and reciprocating movement of said plunger, and means formed on said plunger and operable during the pressure stroke thereof when any one of said discharge passageways is in communication with said pressure space for first cutting off communication between said pressure chamber and said inlet and by-pass passageway, then cutting off communication between said pressure chamber and said single opening of said inlet and by-pass passageway and then reestablishing communication between said pressure chamber and said single opening of said inlet and by-pass passageway, said means also establishing communication between said pressure space and said single opening of said inlet and by-pass passageway during the suction stroke of said plunger.

5. A fuel injection pump for a multi-cylinder internal combustion engine comprising a cylinder having a single combination fuel inlet and by-pass passageway opening into said cylinder through a single opening and a plurality of fuel discharge passageways, a plunger working directly in said cylinder, and means for continuously reciprocating and rotating said plunger in said cylinder, said plunger having an annular peripheral groove therein adapted to communicate directly with said inlet and by-pass passageway when said plunger nears the end of its suction stroke, a single longitudinal peripheral groove extending from said annular groove through the working end of said plunger and adapted to successively register with said discharge passageways in intermittently successive positions of the rotary and reciprocating movement of said plunger and a series of circumfer-

entially spaced longitudinal peripheral grooves of a number corresponding to the number of discharge passageways extending from said annular groove far enough to establish communication between said annular groove and said single opening of said inlet and by-pass passageway in all positions of the reciprocating movement of said plunger.

6. The combination set forth in claim 5 wherein the means for rotating said plunger is adjustable to change the phase relationship between said plunger and plunger rotating means to thereby change the positions of said series of longitudinal grooves relative to said inlet and by-pass passageway and thus vary the quantity of fuel discharged through said discharge passageways and said mentioned means is automatically controlled by means responsive to the speed of rotation of said plunger rotating means.

7. A unit fuel injection and supply pump assembly for a multi-cylinder internal combustion engine comprising a fuel injection cylinder having a combination fuel inlet and by-pass passageway and a plurality of fuel discharge passageways, a plunger working in said cylinder, means for simultaneously reciprocating and rotating said plunger in said cylinder, means formed on said plunger for successively placing said discharge passageways in communication with the pressure space of said cylinder in intermittent successive positions of the rotary and reciprocating movement of said plunger, means formed on said plunger and operable during each pressure stroke thereof for placing said pressure space first in communication with said inlet and by-pass passageway, then cutting off communication between said pressure space and said inlet and by-pass passageway and then reestablishing communication between said pressure space and inlet and by-pass passageway when any one of said discharge passageways is in communication with said pressure space, a fuel supply cylinder communicating with said inlet and by-pass passageway, and a piston working in said fuel supply cylinder and operable by said plunger rotating means for feeding fuel to said inlet and by-pass passageway.

8. The combination set forth in claim 7 wherein said fuel injection and supply pump assembly includes a priming cylinder that communicates with said inlet and by-pass passageway and a priming piston that is manually reciprocable in said last mentioned cylinder.

9. The combination set forth in claim 7, wherein said fuel supply cylinder communicates at both ends with said inlet and by-pass passageway, said piston is a double acting piston, means is provided for equalizing the pressure at both ends of said fuel supply cylinder, and means is provided for by-passing fuel from said fuel supply cylinder at a predetermined pressure at one end thereof.

10. A fuel injection pump for a multi-cylinder internal combustion engine comprising a cylinder having an inlet and by-pass passageway, a plurality of discharge passageways, a plunger working in said cylinder, means formed on said plunger for successively placing said discharge passageways in communication with the pressure space of said cylinder in intermittently successive positions of the rotary and reciprocating movement of said plunger, and means formed on said plunger for placing said pressure space in communication with said inlet and by-pass passageway during the suction and pressure strokes

of said plunger, said plunger reciprocating and rotating means comprising a shaft adapted to be driven by or in unison with said engine, a cam operated by said shaft for reciprocating said plunger, and a connection between said shaft and plunger for rotating the latter, said connection being adjustable to change the angular relationship between said shaft and said plunger to thereby vary the fuel amounts delivered by said pump.

11. The combination set forth in claim 12 wherein the angularly adjustable connection between said shaft and plunger comprises a sleeve supported in an axial bore in said shaft and having a slot extending parallel to the rotary axis thereof and a slot extending at an oblique angle to said axis, a stud fixed to said shaft and extending into said oblique slot, and a member rotatable with said plunger and having a portion extending into said parallel slot.

12. A fuel injection pump for a multi-cylinder internal combustion engine comprising a cylinder having an inlet and by-pass passageway, a plurality of discharge passageways, a plunger working in said cylinder, means formed on said plunger for successively placing said discharge passageways in communication with the pressure space of said cylinder in intermittently successive positions of the rotary and reciprocating movement of said plunger, and means formed on said plunger for placing said pressure space in communication with said inlet and by-pass passageway during the suction and pressure strokes of said plunger, said plunger reciprocating and rotating means comprising a shaft adapted to be driven by or in unison with said engine, a cam operated by said shaft for reciprocating said plunger, and a connection between said shaft and plunger for rotating the latter, said connection comprising a sleeve supported by said drive shaft for rotary and axial sliding movement relative thereto, an axially slid able but non-rotatable connection between said sleeve and plunger, and a pin-and-helical slot connection between said shaft and sleeve.

13. The combination set forth in claim 12, wherein said sleeve is automatically shifted axially of said shaft by means responsive to the speed of rotation thereof to vary the angular relationship of said plunger and shaft.

14. The combination set forth in claim 12, wherein said sleeve is automatically shifted axially of said drive shaft by a governor comprising weights pivotally supported on said shaft and operable under the action of centrifugal force from the axis thereof to move said sleeve axially in one direction, a spring-pressed lever for yieldably resisting such movement of said sleeve, and means for varying the resistance offered by said spring-pressed lever to such movement of said sleeve.

15. The combination set forth in claim 12, wherein said sleeve is automatically shifted axially of said shaft by a governor comprising weights pivotally supported on said shaft and operable under centrifugal force from the axis thereof to move said sleeve axially in one direction, a lever mounted for swinging movement lengthwise of said sleeve with one end in position to be operated by such axial movement of said sleeve, an arm mounted for swinging movement lengthwise of said sleeve, a coil compression spring interposed between said arm and the other end of said lever for yieldably resisting movement thereof by said sleeve, a tension spring

associated with said arm and said compression spring for varying the resistance offered by said compression spring to movement of said lever by said sleeve.

16. The combination set forth in claim 12, wherein said sleeve is automatically shifted axially of said shaft by a governor comprising weights pivotally supported on said shaft and operable under centrifugal force from the axis thereof to move said sleeve axially in one direction, a lever mounted for swinging movement lengthwise of said sleeve with one end in position to be operated by such axial movement of said sleeve, an arm mounted for swinging movement lengthwise of said sleeve, a coil spring interposed between said arm and the other end of said lever for yieldably resisting movement thereof by said sleeve, a tension spring having one end sustained by the free end of said arm, and means cooperating with the other end of said tension spring for varying the tension thereof and the angular relation thereof to the pivotal axis of said arm.

17. The combination set forth in claim 12, wherein said sleeve is automatically shifted axially of said shaft by a governor comprising weights pivotally supported on said shaft and operable under centrifugal force from the axis thereof to move said sleeve axially in one direction, a lever mounted for swinging movement lengthwise of said sleeve with one end in position to be operated by such axial movement of said sleeve, an arm mounted for swinging movement lengthwise of said sleeve, an extensible link extending between said arm and the other end of said lever, a coil compression spring mounted around said link for pressing the ends thereof against said arm and said other end of said lever, a tension spring having one end sustained by the free end of said arm, and a shaft disposed parallel to the pivotal axis of said arm and connected

to the other end of said tension spring for varying the tension thereof and the angularity thereof relative to said arm and said coil compression spring.

18. The combination set forth in claim 12, wherein said sleeve is automatically shifted axially of said shaft by a governor comprising a spider mounted on said shaft, a circumferentially yieldable driving connection between said shaft and spider, weights pivotally supported on said spider and operable under centrifugal force from the axis thereof to move said sleeve axially in one direction, a lever mounted for swinging movement lengthwise of said sleeve with one end in position to be operated by such axial movement of said sleeve, a fixed knife edge, an arm mounted on said knife edge for swinging movement lengthwise of said sleeve, an extensible link extending between said arm and the other end of said lever, a coil compression spring mounted around said link for pressing the ends thereof against said arm and said other end of said lever, a coil tension spring having one end sustained by the free end of said arm, and a manually operable shaft disposed parallel to said knife edge and connected to the other end of said tension spring for varying the tension thereof and the angularity thereof relative to said arm and said compression spring.
